UNITED STATES PATENT OFFICE.

RAY HUBBELL, OF NORTHLIVILLE, NEW YORK.

METAL CORNER FOR OIL-CLOTHS.

SPECIFICATION forming part of Letters Patent No. 224,435, dated February 10, 1880.

Application filed October 21, 1879.

To all whom it may concern:

Be it known that I, RAY HUBBELL, of Northville, in the county of Fulton and State of New York, have invented a new and valuable Improvement in Metal Corners for Oil-Cloths; and I do hereby declare that the following is a full, clear, and exact description of the construction and operation of the same, reference being had to the annexed drawings, 10 making a part of this specification, and to the letters and figures of reference marked thereon.

Figure 1 of the drawings is a representation a top-plan view of a section of oil-cloth 15 with metal corner attached; Fig. 2, an under-side plan view of the same. Fig. 3 is a perspective view of the metal corner.

The object of the present invention is to provide a simple means for protecting the 20 corners of oil and other cloths.

Previous to my invention it was common to bind the edges of oil and other floor-cloths with narrow strips of metal known as "edging," said sheet-metal strips being bent around 25 the four sides of the cloth, covering the edges thereof to protect them and prevent the edges from wearing.

Although the object sought to be accomplished was attained, it required great care 30 and a person skilled in the art to nicely turn or bend the strips of sheet metal around the edges of the cloth, in order to give the same a neat appearance and pleasing effect to the eye.

35 The invention consists in a corner-piece for oil and other floor-cloths formed from a sheet-metal plate, with an upturned flange around the outer edge thereof, whereby it is ready for connecting to the corner of the cloth, as will 40 be hereinafter more fully described.

In the accompanying drawings, A represents a section of a corner of an oil or other floor-cloth, and B the sheet-metal plate which

forms the corner-piece for attaching to the corner of the cloth. This plate B may be of 45 any suitable metal, either ornamental or plain, and of any desired width, and is formed around its outer edge with an upturned flange, b.

The plate B, with its flange b, is preferably formed by suitable dies, whereby a series of 50 the plates B may be stamped at a single operation, the corner pieces or plates thus formed being put up in sets of four or more, and sold in the market, the purchaser being fully capable of attaching them to the corners of the 55 floor-cloth, which is done simply by turning or bending the flange b under the edge of the same after the plate B has been properly placed in position on the upper surface of the cloth, after which the plate is secured by tacks 60 or other simple means.

Thus it will be readily seen that a simple device is provided for the corners of oil or other floor-cloths, which forms a binding to render the corners of the oil-cloth of sufficient 65 rigidity or stiffness to prevent their bending over and breaking, and, when used for other floor-cloths, to give a neat appearance to the corner and prevent them from tearing away from the floor.

Having now fully described my invention, what I claim as new, and desire to secure by Letters Patent, is—

As a new article of manufacture, a corner-piece for oil and other floor-cloths, struck up 75 from a single piece of sheet metal, and consisting of the plate B, having upturned flange b around the outer edge thereof, substantially as and for the purpose set forth.

In testimony that I claim the above I have 80 hereunto subscribed my name in the presence of two witnesses.

RAY HUBBELL.
